UNITED STATES PATENT OFFICE.

MARKS SAMUELS, OF NEW YORK, N. Y.

FOLDING BED.

SPECIFICATION forming part of Letters Patent No. 530,855, dated December 11, 1894.

Application filed April 12, 1894. Serial No. 507,288. (No model.)

To all whom it may concern:

Be it known that I, MARKS SAMUELS, a citizen of the United States, residing at New York, in the county and State of New York, have invented new and useful Improvements 5 in Folding Beds, of which the following is a specification.

This invention relates to an improvement in folding beds the invention consisting in the 10 novel features of construction set forth in the following specification and claim and illustrated in the annexed drawings, in which—

Figure 1 is a front elevation of the bed closed or folded. Fig. 2 is a side elevation of Fig. 1. Fig. 3 is a section along $\alpha\alpha$ Fig. 1. Fig. 4 is a section along $y\gamma$ Fig. 5 the bed being open. Fig. 5 is a plan view of the bed open and sectioned along $z\zeta$ Fig. 4. Fig. 6 is a section along $u\mu$ Fig. 4 enlarged. Fig. 20 7 is a section along $v\nu$ Fig. 6. Fig. 8 is a section along $w\omega$ Fig. 1 enlarged.

The letters A B indicate the folding bed frame sections. The non-folding, stationary main frame or section A stands upright and 25 may be closed, but for ventilation it is preferable to leave said back open, suitable strips or cross pieces C being applied at intervals along the back for giving the requisite strength. At the sides along the bottom of 30 section A are also strips D for giving strength and finish.

The section A has suitable sockets or seats into which can be slipped the studs or pivots E of section B so that the latter section can 35 suitably swing or fold.

The foot or free end of section B has legs F secured to a cross piece or plank G jointed to section B at H and when the section B is down or open the legs swing out to support 40 the foot of said section B. The legs are held in their supporting position by a brace K jointed to plank G at I and locking against an end or edge of the fixed or rigid bottom L of section B, (Fig. 4.) This bottom L is made 45 to terminate some distance from the free end or foot of section B, said lock or brace K pressing its free end against the edge of bottom L to hold the legs F in supporting position. When the device is closed or folded 50 the brace K is slipped or swung off bottom L

and into the space between the edge of said bottom and the foot of section B (Fig. 3) so as to be housed or concealed. The cross plank G covers the space between end of bottom L and the foot of section B when the latter is closed. 55

The lower side parts of section A where the pivots E are located are made to project forward some distance so that the bed is lengthened without the sections A B standing excessively high when the device is closed, and the section B has panels or strips M made to project or flange beyond the edges of section B and made to conform to the front edges of section A so that when the 60 device is closed the panels or flanges M will set closely to the front edges of section A (Fig. 2) to conceal joints or seams.

The section B has a foot board N secured to arms O jointed at P to section B so that 65 the foot board N can be swung from the position shown in Fig. 4 into section B (Fig. 3) when the latter is to be closed.

To the cross piece Q in section B is secured 70 one end of a flexible bottom R, the other end thereof being secured to a cross piece C by a suitable holder or fastening such as a cross piece S and bolts T. Intermediate its ends the flexible bed bottom R is secured to a cross piece U forming part of a frame, the side 75 parts or strips V of the frame being fixed or bolted at W W to the section B. The ends of the strips V being thickened at the parts receiving said bolts or fastenings W, said ends will be sufficiently strong for securing 80 firm connection, and the portions of strips V extending from fastenings W toward cross piece U being somewhat thinned, and being left free or unfastened, said cross piece U will be elastically or yieldingly supported so 85 as to give to the weight of a body on the flexible bottom.

The section B has cut out portions forming 90 lugs or projections X under which extend the ends of cross piece U projecting beyond 95 the side strips V. These lugs or stops X prevent the cross piece U rising above or out of the section B but allow said cross piece with the flexible bottom to yield to a weight on the latter. The cross piece U to which 100

the flexible bottom is secured keeps that part of said flexible bottom between said cross piece U and cross piece Q permanently stretched, as well when the section B is open as when it is closed.

To the section B at Y are jointed links Z and to the section A at α are jointed links b, said links being jointed to one another at c. One of the links carries a cross piece d, provided with springs e. When the bed is open (Fig. 4) the links are raised or swung up so that the springs e support the head part of the flexible bottom. When the bed is closed (Fig. 3) the links drop so as to allow the head part of the flexible bottom to curve or bulge whereby space is offered for accommodating bedding between the closed sections A, B.

The bulging or enlarged portion of section B at the hinges E offers space into which can be inserted a drawer f and a suitable lock or catch can be made to hold the drawer in place against dropping out when the section B is swung open.

The section B if desired can be provided in any well known way with springs (not

shown) for supporting the flexible bottom R at suitable intervals.

What I claim as new, and desire to secure by Letters Patent, is—

The combination with a stationary non-folding upright frame A, a folding bed frame B, and a flexible bed bottom R secured at one end to the upright frame, and at the other end to the folding bed frame, of supporting links b and Z jointed together at 35 their adjacent ends and respectively pivoted to the said stationary upright frame and the folding bed frame, a cross-bar d secured to the links b between their pivoted ends, and springs e carried by the cross-bar and supporting the head portion of the flexible bed bottom when the bed is unfolded, substantially as described.

In testimony whereof I have hereunto set my hand in the presence of two subscribing witnesses.
